UNITED STATES PATENT OFFICE

ERNST GALLE, OF LUDWIGSHEAFEN-ON-THE-RHINE, AND GERHARDT HOFMANN AND HERMANN ZORN, OF MANNEHIM, GERMANY, ASSIGNEES TO I. G. FARBEININDUSTRIE AKTIENGESELLSCHAFT, OF FRANKFORT-ON-THE-MAIN, GERMANY, A CORPORATION OF GERMANY

PRODUCTION OF HYDROCARBONS OF LOW BOILING POINT

No Drawing. Application filed September 3, 1927, Serial No. 217,532, and in Germany September 3, 1926.

The present invention relates to the production of hydrocarbons of low boiling point from hydrocarbons of high boiling point of any origin, for example from tars, mineral oils and the like.

We have found that the said hydrocarbons of high boiling point can be converted into products of lower boiling point by acting on them with a gaseous halogen hydride at temperatures above 100° C. in the presence of activated metals or alloys. By this term we mean metals and alloys which have been rendered particularly reactive by treatment with solutions of metal salts.

It has been found that in this process especially aluminium, but also numerous other metals, such as copper, lead, magnesium, iron, cobalt, chromium and the like and also alloys thereof, have a particularly good effect in the production of low-boiling products when employed in an activated condition. The activation of the metals and alloys is effected by treating the same with a solution of a salt of such metal which in the electromotive series (see for instance Alexander Smith "Introduction to Inorganic Chemistry", 3rd edition, page 404) ranges below the metal to be activated and which is solid at room temperature. By this treatment the metal of the salt is precipitated in a state of fine distribution in the metallic or oxidic form upon the catalytic metal to be activated. This activation proceeds most effectively when the metal or alloy has been etched beforehand with caustic soda solution, hydrochloric acid or the like, if necessary after washing with alcohol or ether. The catalysts prepared in this manner are excellently adapted for the conversion of tars and mineral oils, and their distillation products and the like with or without the application of elevated pressure. In some cases, especially favorable yields may be obtained if the activated metals, instead of being used alone, are employed in admixture with anhydrous metal chlorides and in particular anhydrous aluminium chloride. The operation is preferably conducted while stirring.

The process according to the present invention is applicable to tar oils, also to tars

generally such as producer tar, and also to hydrocarbons of any other origin, such as mineral oils, shale oils, products obtained by the destructive hydrogenation or by the extraction of carbonaceous materials such as 55 coals, tars and mineral oils and the like. The process is also adapted for the treatment of such portions of mineral oils as are soluble in liquid sulfuric acid, which portions have hitherto been regarded as useless. Products 60 containing 20 to 30 per cent and more of benzene and toluene, in addition to other light hydrocarbons, and which are therefore particularly suitable as motor fuels, can be obtained according to this process. 65

By treating for example a crude mineral oil poor in low boiling constituents with activated aluminium and hydrochloric acid gas, at temperatures over 100° C., approximately 80 per cent of products boiling up to 200° C. 70 are obtained.

The valuable hydrocarbons of low boiling point obtained by this process need not be purified by troublesome and expensive operations, but it is sufficient to wash them with 75 dilute caustic soda solution or to subject them to steam distillation. The products are clear and colorless and do not become colored by the action of light and air. They are practically completely saturated and consist of paraffin hydrocarbons, naphthenes or 80 aromatic hydrocarbons, or mixtures thereof in varied proportions, depending on the nature of the initial materials employed.

We have further found that the yield in 85 valuable saturated aliphatic hydrocarbons of very low boiling point may be considerably increased; to this end aliphatic or naphthenic hydrocarbons of high boiling point are passed through the reaction chamber at so 90 low a velocity that considerable quantities of hydrocarbons boiling below 70° C. are formed. With this end in view, the rate of flows should be suitably accommodated to the other working conditions having regard for 95 example to the nature of the initial material and contact mass, the temperature and the like, and an example of this mode of working illustrating the influence of the rate of flow in the case of a mineral oil fraction will 100

be given hereinafter. With other initial materials and other catalysts etc., the speed must again be adapted to the circumstances of each particular case.

5 The recovery of the low-boiling cracked products may be effected by strong cooling or compression, or both, or by means of adsorption or absorption agents, preferably in such a manner that fractionation occurs at 10 the same time.

15 The requisite heat is preferably supplied to the reaction chamber by external heating and by preheating the initial material. The operation may also be carried on in the presence of inert gases, such as hydrogen, or nitrogen, or vapors.

20 The following examples will further illustrate the nature of the said invention which however is not limited thereto. The parts are by weight.

Example 1

Activated aluminium turnings are allowed to act, in the presence of dry hydrochloric acid gas, on 100 parts of an Elwerat crude mineral oil, in a vessel lined with Monel metal and provided with a stirrer. The treatment is carried out at temperatures rising from 100° to 180° C. The aluminium is activated by purifying aluminium turnings with ether-alcohol and etching this pre-treated material with dilute caustic soda solution. After rinsing the material with water, it is subjected to the action of a 1 per cent solution of uranium nitrate. The mineral oil yields 80 parts of constituents boiling up to 200° C.

Example 2

40 100 parts of producer tar from brown-coal are heated to above 150° C. with 10 parts of granular aluminium activated by zinc chlorid, a current of hydrochloric acid gas being passed through while stirring. 70 45 parts of a liquid product are obtained, of which about 50 per cent up to 200° C.

Example 3

50 100 parts of a fraction boiling from 200° to 400° C. of a product from the destructive hydrogenation of coal by treatment with hydrogen under pressure are treated at temperatures from 120° to 160° with dry hydrochloric acid gas, while stirring and in the presence of aluminium turnings activated by copper chlorid. 77 per cent of a distillate are obtained, of which 78 per cent boils up to 200° C.

Example 4

60 100 parts of a portion of mineral oil which is soluble in sulfurous acid are heated to from 150° to 220° with 1 part of aluminium turnings activated by uranium nitrate and 1 part of aluminium turnings activated by silver nitrate, while passing through hydro-

chloric acid gas. 53 per cent of a distillate are obtained, 25 per cent of which consists of benzene and toluene.

Example 5

70 700 parts of such portions of a mineral oil as are soluble in liquid sulfurous acid, are heated to 170° C., while actively stirring, with 14 parts of anhydrous aluminium chlorid and 14 parts of granular aluminium 75 activated by silver nitrate, dry hydrogen chlorid being passed through. 60 per cent of a distillate boiling below 200° C. are obtained, 32 per cent of which consists of benzene and toluene.

Example 6

80 The following typical example demonstrates clearly the influence exerted on the character of the products by the rate of flow 85 of the initial material through the contact chamber.

85 By passing a mineral oil fraction, boiling between 220 and 285° C. at the rate of 100 cc. per hour through a contact chamber of 500 90 cc. capacity, charged with sheet aluminium activated by nickel chlorid and heated to 200° C., with the addition of hydrogen chlorid, there is obtained, in an air-cooled receiver, 84 per cent of a condensate, 31 per cent of 95 which boils between 70° and 200° C. in addition to which 10 per cent of condensate is obtained by strongly cooling to the temperature of solid carbon dioxid. On the rate of flow being reduced to one-third, the air-cooled receiver contains 50 per cent of condensate, 47 per cent of which boils between 70° and 200° C. whilst strongly cooling furnishes 44 per cent of condensate. On lowering the rate of flow to one-sixth, 96 per cent 105 of condensate is obtained in the strongly cooled receiver, whereas air-cooling furnishes no condensate at all. The condensates obtained by cooling to the temperature of solid carbon dioxid, consist of a small amount of 110 ethane, 10 to 20 per cent of propane, 30 to 40 per cent of butane, 30 to 40 per cent of pentane and 5 to 10 per cent of hexane.

What we claim is:

115 1. The process of producing hydrocarbons of low boiling point which comprises acting on hydrocarbons of high boiling point with a gaseous halogen hydrid at temperatures above 100° C. in the presence of an activated metal selected from the group consisting of 120 aluminium, copper, lead, magnesium, iron, cobalt, chromium and alloys thereof, said metal being activated by treatment with a solution of a salt of a metal which is solid at room temperature and which in the electro-motive series of the metals ranges below the metal to be activated.

125 2. The process of producing hydrocarbons of low boiling point which comprises acting on hydrocarbons of high boiling point with 130

hydrochloric acid gas at temperatures above 100° C. in the presence of aluminium activated by a treatment with a solution of a salt of a metal which is solid at room temperature and which in the electromotive series ranges below aluminium.

3. The process of producing hydrocarbons of low boiling point which comprises acting on hydrocarbons of high boiling point with hydrochloric acid gas at temperatures above 100° C. in the presence of aluminium activated by a treatment with a solution of a salt of a metal, which is solid at room temperature and which in the electromotive series of the metals ranges below aluminum, and aluminium chlorid.

4. The process of producing hydrocarbons of low boiling point which comprises acting on hydrocarbons of high boiling point with a gaseous halogen hydrid at temperatures between 100° and 220° C. in the presence of a metal selected from the group consisting of aluminium, copper, lead, magnesium, iron, cobalt, chromium and alloys thereof said metal being activated by treatment with a solution of a salt of a metal which is solid at room temperature and which in the electromotive series of the metals ranges below the metal to be activated.

30 5. The process of producing hydrocarbons of low boiling point which comprises acting on hydrocarbons of high boiling point with a gaseous halogen hydrid at temperatures between 100° and 220° C. in the presence of a metal of the group of metals which are electropositive to copper and including copper, activated by a treatment with a solution of a salt of a metal which is solid at room temperature and which in the electromotive series of the metals ranges below the metal to be activated.

6. The process of producing hydrocarbons of low boiling point which comprises acting on hydrocarbons of high boiling point with hydrochloric acid gas at temperatures between 100° and 220° C. in the presence of aluminium activated by a treatment with a solution of a salt of a metal which in the electromotive series ranges below aluminium.

50 7. The process of producing hydrocarbons of low boiling point which comprises acting on hydrocarbons of high boiling point with a gaseous halogen hydrid at temperatures above 100° C. in the presence of a metal of the group of metals which are electropositive to copper and including copper which is activated by a treatment with a solution of a salt of a metal which is solid at room temperature and which in the electromotive series of the metals ranges below the metal to be activated.

8. The process of producing hydrocarbons of low boiling point which comprises acting on hydrocarbons of high boiling point with a gaseous halogen hydrid at temperatures above 100° C. in the presence of a metal of

the group of metals which are electropositive to copper and including copper which is activated by a treatment with a solution of a salt of a metal which is solid at room temperature and which in the electromotive series of the metals ranges below the metal to be activated and an anhydrous metal chlorid.

9. The process of producing hydrocarbons of low boiling point which comprises acting on non-aromatic hydrocarbons of high boiling point with a gaseous halogen hydrid at temperatures above 100° C. in the presence of a metal of the group of metals which are electropositive to copper and including copper which is activated by a treatment with a solution of a salt of a metal which is solid at room temperature and which in the electromotive series ranges below the metal to be activated, the speed of the said non-aromatic hydrocarbons being chosen so low that considerable quantities of hydrocarbons boiling below 70° C. are formed.

10. The process of producing hydrocarbons of low boiling point which comprises stirring hydrocarbons of high boiling point with a gaseous halogen hydrid at temperatures above 100° C. in the presence of a metal of the group of metals which are electropositive to copper and including copper which is activated by a treatment with a solution of a salt of a metal which is solid at room temperature and which in the electromotive series of the metals ranges below the metals to be activated.

In testimony whereof we have hereunto set our hands.
